UNITED STATES PATENT OFFICE.

HENRI GOUGNARD, OF AHN-LEZ-HUY, BELGIUM, ASSIGNOR TO SOCIÉTÉ BELGE DES PRODUITS RATIONNELS, SOCIÉTÉ ANONYME, OF AHN-LEZ-HUY, BELGIUM, A COMPANY.

RESPIRATION GYMNAStic APPARATUS.

Application filed March 16, 1927, Serial No. 175,905, and in Belgium March 18, 1926.

My invention relates to a respiration gynastic apparatus which has for its object to increase the respiratory amplitude by a training, the progresses of which may be easily controlled. Apparatuses and processes of this kind hitherto known do not allow the patient to watch the progresses of his training; these progresses taking place unknown to the patient, and the want of control precluding the necessary emulation; the consequence is, generally, a want of perseverance and also the loss of benefit of the training.

In order to avoid the disadvantages of these apparatuses it has been suggested to make use of apparatuses in which the displacement of a level of water indicates by difference the quantity of air which has been blown in. In these apparatuses, the inspiration following the expiration has the same amplitude and is gradually increasing, the lung adapting itself very quickly to the more active working which is required from it. In other known apparatuses, use is made of the displacement of air, but these apparatuses are, in reality, spirometers and not training apparatuses. All these apparatuses present great disadvantages: those in which use is made of a displacement of water, have a great resistance which is considered by the physiologists as excessive and also dangerous. Moreover, their handling is less easy and requires the intervention of a third person. Further, none of the known apparatuses can work with the speed of the respiratory rhythm although now the condition of the training is the judicious control of the repetition of the effort.

My apparatus has for its object to avoid these disadvantages to do away with all excess of resistance and to obtain continuity in the working, and is characterized by this fact that during inspiration an instantaneous manœuvre, which can be carried out by the patient, the apparatus is ready for the following blowing in.

With this object in view my invention essentially consists in a special arrangement and combination of parts hereinafter fully described and pointed out in the appended claims.

Referring to the annexed drawing, which shows an example of embodiment of my invention:

1 is a transparent cylinder for instance in glass in which a circular plate 2 is disposed this plate having a diameter equal to that of the cylinder 1. This plate 2 can slide on a guide 3 arranged in the center of the cylinder 1 which carries a graduation 4. By means of the plate 2 the cylinder 1 is divided into two chambers 5 and 6. The two chambers 5 and 6 are connected each to a pipe, the chamber 5 to a pipe 7 and the chamber 6 to a pipe 8. These two pipes 7 and 8 are connected to a common pipe 9 through a cock 10 movable by hand and provided with an outlet 11 opening in the atmosphere.

The plate 2 may be provided with a stop 12 of variable length according to the point of the cylinder 1, where the pipe 8 is connected, with respect to the extremities of the said cylinder 1 so as to avoid the blocking of the apparatus.

The working of the apparatus is the following: the deficiency in the respiratory capacity of the patient having been ascertained by means of a spirometer, the number of expirations and the volume of air which will be blown in at each expiration will be fixed.

The patient will afterwards blow into the pipe 9 and the air which is breathed out will pass through the cock 10 into one of the chambers of the apparatus (in the example shown into the chamber 5) and will act upon the plate 2 which will be displaced along the graduation 4 and which will cause a flowing back of the air contained in the chamber 6 through the pipe 8. The expiration will be stopped when the plate 2 will have reached the graduation corresponding to the quantity of air which has been fixed. At this moment the greater the volume of air which has been expelled, the more deeply will then the patient inhale. But at this moment also he will turn the cock through 90° so that the air of the following blowing in will pass into the chamber 6 and will bring again the plate 2 to the graduation point zero. In both cases the air, which is in the chamber opposite to that into which the patient blows, will not be compressed and will be acted upon by the plate 2, will be conducted by one of the pipes 7 or 8, and will be finally expelled through the outlet 11.

It will be easily understood that the cock 10 may be omitted. In this case the patient

blows alternatively into the two tubes 7 and 8. It is however more easy to blow into a single pipe provided with a cock.

It will be observed that the advantages of the apparatus are the following:

(1) The quantities of air blown in are always equal, whatever may be the direction, and are easily adjusted.

(2) The exercises may take place successively and without any interruption nor uneasy or tiring manœuvre, and this within the limits prescribed by the doctors.

(3) The resistance of the apparatus is very slight and cannot be in any way a cause of fatigue to the patient.

(4) The patient may follow de visu the progresses of his training.

(5) He does not need any help in order to manœuvre the apparatus.

What I claim is:

1. In a respiration apparatus, a transparent airtight cylinder having an interior longitudinal rod, a plate fitted to the interior of said cylinder and slidable upon said rod, a scale on said cylinder to indicate the position of said plate, inlet pipes communicating with the interior of said chamber near its ends and on either side of said plate, a third pipe and a cock connecting each of said inlet pipes alternately with said third pipe and with the atmosphere.

2. In a respiration apparatus, an elongated

airtight chamber having an interior longitudinal guide, a plate fitted to the interior of said chamber and movable along said guide, the wall of said chamber permitting vision of said plate from the exterior, a scale applied to the chamber in a position adjacent the plate for indicating the position of the same, and pipes communicating with the interior of said chamber near its ends and on either side of said plate.

3. In a respiration apparatus, an airtight chamber having a capacity corresponding substantially to the volume of air expellable by the human lungs, a slideable piston in close engagement with the interior surface of said chamber, the wall of said chamber permitting vision of said piston from the exterior, a scale applied to the chamber in a position adjacent the piston for indicating the position thereof, and openings communicating with the interior of said chamber at or near its ends on either side of said piston, the piston having such lightness and freedom of movement as to be movable by the expiratory action of breathing without undue or unnatural effort on the part of the user, whereby the piston may be caused to traverse the chamber by respiratory action maintained with the rhythm of natural breathing.

In testimony whereof I have affixed my signature.

HENRI GOUGNARD.
